UNITED STATES PATENT OFFICE

170,440

PORTABLE FLUID DISPENSING UNIT

Winfield W. Alsup, Shreveport, La., assignor to
The J. B. Beard Company, Inc., Shreveport,
La., a corporation of Delaware

Application April 17, 1953, Serial No. 24,566

Term of patent 14 years

(Cl. D52—2)

To all whom it may concern:

Be it known that I, Winfield W. Alsup, a citizen of the United States, residing at Shreveport, parish of Caddo, State of Louisiana, have invented a new, original, and ornamental Design for a Portable Fluid Dispensing Unit, of which the following is a specification, reference being had to the accompanying drawing, forming a part thereof.

I claim:

The ornamental design for a portable fluid dispensing unit, as shown.

WINFIELD W. ALSUP.
